UNITED STATES PATENT OFFICE.

HERMAN T. KOERNER, OF BUFFALO, NEW YORK.

PRINTER'S DRYING-RACK.

SPECIFICATION forming part of Letters Patent No. 504,985, dated September 12, 1893.

Application filed January 21, 1893. Serial No. 459,077. (No model.)

To all whom it may concern:

Be it known that I, HERMAN T. KOERNER, a citizen of the United States, residing at Buffalo, in the county of Erie and State of New York, have invented certain new and useful Improvements in Printers' Drying-Racks; and I do hereby declare the following to be a full, clear, and exact description of the invention, such as will enable others skilled in the art to 5 10 15 20 25 30 35 40 45 which it appertains to make and use the same, reference being had to the accompanying drawings, and to figures of reference marked thereon, which form a part of this specification.

My invention relates to that class of drying racks or trays adapted for lithographers' or printers' use, and consists of certain improvements in that form of interchangeable rack or tray for which Letters Patent No. 392,735 were granted to me on the 13th day 20 25 30 35 40 45 of November, 1888. This certain rack or tray consisted essentially of a floor piece or pieces having secured thereto on each side a rail, each rail having an inner wall, a shelf or recess above the inner wall, a guard along the outside of the shelf or recess and an outside groove below the guard adapted for sliding register with the guard of the rack placed beneath.

The object of my present invention is the production of a rack or tray having a rail which is much more compact than my former rail, and which can be more rigidly secured to the floor piece or pieces, and to that end my invention consists essentially of a floor 30 35 40 45 piece or pieces having secured thereto on each side a rail, each rail having an inner wall, a shelf above the inner wall, an outside groove adjacent to the shelf, and opposite to the inner wall, and a depending guard underneath the outside groove and projecting below the floor piece adapted for sliding register with the outside groove of the rack placed beneath and a recess above the depending guard forming a shelf for the reception of the end of the floor piece.

I will now minutely describe the manner in which I have carried out my invention.

In the drawings, Figure 1 is an under side

view of one of my improved racks or trays. 50 Fig. 2 is an elevation of a series of the racks forming a drying stack. Fig. 3 is an enlarged partial section taken in the line $x-x$ of Fig. 1.

Referring to the drawings, 1. 1. are the floor 55 pieces secured to the rails preferably at intervals so as to form open spaces between them. Along the ends of these floor pieces are the rails 2. 2. to which they are joined. Each rail consists of an inner wall 3 of the 60 depth of the tray. Above this wall 3, and at right angles thereto, is the narrow shelf 4 forming a rest for the contiguous end of the rack above it.

5 is the outside groove adjacent to the shelf 65 which is cut across the upper and outer corner of the rail.

6 is the guard underneath the outside groove 5, and depending below the floor 1 of the rack.

7 is the under side of the rail between the 70 inner wall 3, and the depending guard 6, and to which the ends of the floor pieces 1 are secured by screws 8, and 9 is a recess which receives the extreme ends 10 of the floor pieces, thereby forming a rest 11 for these 75 ends and insuring additional stability of parts.

It will thus be seen that the construction just described involves a very compact form of rail to which the floor pieces are very rigidly secured, both by the fastening screws and the recess 9 with its shelf 11. In forming the stack or nest of racks or trays, the depending guards 6, 6, on either side register accurately with the outside grooves 5 of the 85 rack beneath them which enables them to be slid on or off from each other as required.

It will be observed that my improved racks or trays are interchangeable one for the other.

I claim—

An interchangeable rack or tray for lithographers' or printers' use, consisting essentially of a floor piece or pieces, having secured thereto on each side a rail, each rail having an inner wall, a shelf or rest above the inner wall, an outside groove adjacent to the shelf and opposite to the inner wall, a depending guard underneath the outside groove and pro-

jecting below the floor piece adapted for sliding register with the outside groove of the rack placed beneath, and a recess above the depending guard forming a shelf for the reception of the end of the floor piece, all arranged in a series as shown to form a drying stack for printed sheets, substantially as described.

In testimony whereof I have signed my name to this specification in the presence of two subscribing witnesses.

HERMAN T. KOERNER.
